UNITED STATES PATENT OFFICE

PHILIP MUELLER, OF DECATUR, ILLINOIS, ASSIGNOR TO H. MUELLER MANUFACTURING COMPANY, OF DECATUR, ILLINOIS, A CORPORATION OF ILLINOIS.

SOCKET-HEAD FOR CURB-COCKS.

1,032,492.

Specification of Letters Patent. Patented July 16, 1912.

Application filed March 28, 1911. Serial No. 617,515.

To all whom it may concern:

Be it known that I, PHILIP MUELLER, a citizen of the United States, residing at Decatur, in the county of Macon and State 5 of Illinois, have invented new and useful Improvements in Socket-Heads for Curb-Cocks, of which the following is a specification.

This invention relates primarily to a 10 socket head for curb cocks, but it may also be used on any part requiring to be turned by a removable key or equivalent implement.

The object of the invention is to provide 15 the turning plug of a cock or other part to be turned with an integral or detachable socket member so arranged that when a key of the proper shape is inserted in the socket to turn the plug, if there be any accumulations of dirt or other matter in the socket, 20 the end of the key when inserted, will force such accumulations out of the socket through suitably disposed openings at the bottom thereof. These openings may be of any number, shape, and size desired to 25 permit easy escape of the accumulations. Furthermore, the openings prevent water collecting in the socket and, in cold weather, freeze and break the socket member.

The socket head of the present invention, 30 in its detachable form, may be made with a polygonal shank or a polygonal socket to be detachably connected, respectively, to a plug or other object having a similarly shaped socket or projecting stem.

35 The following detail description of the invention will, for the sake of clearness, be confined to its application to curb cocks, it is to be understood however that the claim is intended to cover the structure broadly 40 and for all uses to which it is adapted.

In the accompanying drawing:—Figure 1 is a vertical sectional view of the invention in its detachable form applied to a socketed cock plug. Fig. 2, a similar view slightly 45 modified showing the socket head detached from the cock. Figs. 3 and 4, plan views partly in section of Figs. 1 and 2 respectively. Fig. 5, a vertical sectional view of the type of socket head illustrated in Fig. 1 50 modified to fit a cock plug formed with a polygonal projecting head or stem, and Fig. 6, a vertical sectional view of a socket head cast integral with the turning plug.

In the drawings, in which like reference 55 characters are used for the same parts in all

the figures, 10 indicates the body of a curb cock and 11 its turning plug such as are in common use. The plug 11 may have either a socket 12 in its upper end as in Fig. 1, or a projecting head or stem 13 shown in Fig. 5. 60

The numeral 14 designates the socket head forming the subject matter of this invention, from the bottom of which projects a stem 15, see Figs. 1 and 2, provided with a plurality of angular ribs 16, preferably 65 four in number, to engage the corners of the socket 12 of the turning plug which is generally square in cross-section. The socket head is retained in place by a bolt 17 threaded in the socketed extension of the 70 plug 11 and bearing against a flattened surface on one of said angular ribs.

The modified form of the socket head represented in Fig. 5 is provided with a square socket 18 in its under side to fit over 75 the square head 13 of the plug 11, and is affixed thereon by a pin seated in registering holes in the head 13 and the lower end of the socket head 14.

The socket head 14 is formed with a chamber or socket 19 extending downwardly for a suitable distance from its top, the lower part of which chamber or socket is preferably of circular, and the upper part 20 of polygonal, cross-section, preferably square 85 to receive the squared end of a suitable operating key. If desired, the chamber or socket 19 may be of polygonal cross-section throughout its length. The sides of the polygonal part 20 flare more or less from 90 above downwardly, there being an outward bevel at the top to assist in centering the key. Through the walls of the socket head 14 at the bottom of the chamber 19 are openings 21, two being shown in Figs. 1 and 95 3 and four in Figs. 2 and 4. The number of openings, however, is optional. The floor 22 of the chamber 19 inclines from the center of the chamber toward the openings 20, the bottoms of said openings being continuous with said floor. The tops also, as well as the sides of the openings preferably flare outwardly as in Figs. 1, 3 and 4. 100

From the above description, and an inspection of the drawings, it will be noted 105 that the chamber or socket 19 gradually enlarges from its upper end to its floor 22, owing to the flaring sides of the polygonal portion, the circular portion of said chamber has a greater diameter than the distance be- 110

tween opposite corners of said polygonal portion at its lowermost and widest part. The openings also gradually increase in size from within outwardly, so that, if the chamber or socket be filled with dirt, as is common, pressure by the key on this accumulation forces it downward and thence out through the openings, the movement of the accumulation being assisted, and packing thereof prevented by the gradual enlargement of the passages in the direction of movement, through which the dirt is forced.

The above type of socket head is designed to be applied to finished cocks, but in Fig. 6 is shown a turning plug 11^a with a socket head 14^a formed integral therewith, the socket head proper being in all respects the same as that shown in the preceding figures with two, four or any desired number of openings 21. In this form of the device the socket head will be lower or nearer the turning plug 11^a because of the omission of the socket 12 or the head or stem 13 from the plug.

The openings 21 may vary both in shape and size to any extent desired, Figs. 2 and 6 showing circular openings, while Fig. 5 shows rectangular openings of greater width than height. In Fig. 1 the openings 21 are made both wide and high, in fact, they may

be as great or greater in area than the upper polygonal part 20 of the socket 19 so that any article, such as a pebble, a piece of stone, or a piece of brick falling through said upper end can be pushed outward 35 through one of said openings.

What I claim is:—

A device of the character described comprising a socket head having a cylindrical chamber therein and a polygonal passageway connecting said chamber to the upper end of the socket to receive a turning member, said passageway increasing in width from above downwardly and of less cross-sectional area at any part thereof than said chamber, said chamber having a plurality of passages opening outwardly therefrom in lateral directions, increasing in size as they progress, the floor of said chamber inclining from the center thereof toward each lateral opening and being continuous with the lower side of the opening.

In testimony whereof I have hereunto set my hand in presence of two subscribing witnesses.

PHILIP MUELLER.
